RECORDING SYSTEM

Livingston Middleditch, Beverly Hills, Calif.

Application July 5, 1938, Serial No. 217,548

5 Claims. (Cl. 274—11)

This invention relates to a method of recording impulses, and more particularly to a method of producing a sound record for reproduction by photosensitive cell and electrical means.

It is common to record sound, or other impulses having frequencies comparable with sound frequencies, either by the original phonographic method of sound-on-wax recording, or by the later developed photographic method of sound-on-film recording. While each of these methods is admirably suited to particular purposes, they each have certain disadvantages, and there are many every-day instances in which sound recording would be desirable to which these methods do not conveniently or economically apply. A few such instances are: for recording extended dictation, conferences, judicial proceedings, lectures, radio programs, and telephone conversations; for taking telephone messages when no one is present; and as a more rapid medium than Braille printing for the use of the blind.

One obstacle in the way of extensive everyday use of sound recording in these fields has been the fact that recording, especially by the photographic method, has been a highly technical procedure and not readily simplified for the layman. Another obstacle no less serious has been the high cost of the record carrier per hour of recording time. Wax and acetate discs or cylinders are expensive, and, if kept as permanent records, inconvenient and expensive to store. Photographic film is expensive in itself, and to this must be added the cost of development and other processing. Paper tape, $\frac{1}{4}$ inch wide, as used for the record carrier in several embodiments of this invention, costs but a small fraction of the amount per hour for the record carrier when using either of these other methods.

An object of this invention is to provide a method of recording so simple in operation that it can be carried out by a person relatively inexperienced (or even unattended), and suitable for recording in the home, school, or business office.

Another object of the invention is to provide a method of recording so economical in operation as to make it suitable for extensive application in the fields mentioned above.

The sound-on-wax method has the disadvantage of limited playing time on a single recording surface, unless the surface be of unreasonable size, and it offers no easy method of editing or rearranging a record after it has been made. Sound-on-film recording overcomes these two difficulties, but at the same time it has the disadvantage that a recording must be processed in

the photographic laboratory before it is ready for use.

It is an object of this invention to provide a method of producing a record that can be compactly stored and that can be played back immediately, without the delay or cost of photographic developing or other processing.

Another object of this invention is to provide a method of producing a record that can be readily edited, corrected, or rearranged after recording.

In order to accomplish these objects, use is made of a printing member that operates mechanically to mark a moving tape in accordance with the impulses to be recorded. This marking may be accomplished through an inking medium or by carbon paper. It is another object of this invention to provide a simple form of recorder whereby these impulses may produce either a variable density record, or a variable area record, or a combination thereof.

Although the primary objects stated have to do principally with the making of sound records, it is a further object of this invention to supply a convenient method of recording varying impulses of any sort, such as those accompanying telegraphic transmission of code, facsimile, pictures, transient electrical phenomena, sonic control of automatic machines or devices, etc., either for purely record purposes or for later utilization by photo-electrical means.

The record or sound track is formed by a succession of marks formed on the record blank by movement of the recording member in a direction which has a component normal to the surface of the blank, in response to impulses supplied to the member by suitable translating mechanism. Thus, the spacing of the marks depends on the frequency of the impulses, or sounds, being recorded, while the width of the marks depends on the strength of the impulses or volume of the sound.

Where a recording member having a straight edge, as member 8 of Fig. 1 or member 16 of Fig. 4, is used, a sound track 18 of uniform width and variable density is formed. If a recording member which has an arcuate edge is used, as member 22 of Fig. 4, or member 27 of Fig. 5, the sound track will be a combination of variable area and variable density, since the recording member will act as before to produce a variable density record. In addition, however, the curved recording member will when it makes a deep impression in response to strong impulses, make these impressions longer, as well as denser, as indicated in

sound track 21 of Fig. 4, than the impressions made in response to weaker impulses. Thus it may be said that the length of the individual marks of the sound track, or the width of the sound track is a function of the pressure exerted by the recording member. The very practical advantage of such a combination track over either variable width or variable density alone, is that it increases the volume range of impulses that can be recorded on a given width of sound track. It is highly desirable that the sound track be narrow, say only .1 inch wide as in sound motion pictures.

This invention possesses many other advantages, and has other objects which may be made more easily apparent from a consideration of several embodiments of the invention. For this purpose there are shown a few forms in the drawing accompanying and forming part of the present specification. These forms, which illustrate the general principles of my invention, will now be described in detail; but it is to be understood that this detailed description is not to be taken in a limiting sense, since the scope of my invention is best defined by the appended claims.

Referring to the drawing:

Figure 1 shows the printing member in schematic form, in operative relation to a tape, and a fine line that constitutes a single elementary impression;

Fig. 2 shows in schematic form a recording machine suitable for use with the method of recording that comprises this invention;

Fig. 3 shows in schematic form an embodiment of the invention in which the printing member is vibrated normally to the face of the record carrier, giving a variable density recording;

Fig. 4 shows in schematic form another embodiment of the invention, in which the face of the printing member is a plane curved knife edge vibrated normally to the face of the record carrier, and giving a record that is both variable area and variable density;

Fig. 5 is a schematic section of another form of the invention in which pigment is supplied by a carbon paper ribbon passed between the printing face and the record carrier;

Fig. 6 is a schematic section of still another form of the invention in which the printing face is the periphery of a rotating sharp-edged disc supplied with ink by an inking roller; and

Fig. 7 is a cross section of an alternative form of printing member in which ink is supplied to a slit-shaped recess (here shown as an annular recess between two rotating discs), the printing being done from intaglio; and

Fig. 8 is a schematic partial sectional view of the form of the invention illustrated in Fig. 7, taken along a plane normal to Fig. 7.

In Fig. 1 a record blank 1 is shown as receiving a record impression. This record blank will usually be in the form of a flexible paper tape, but any other thin flexible material capable of receiving the impression, such as Celluloid, or even thin metal, may be used. If the tape 1 be made of material that is transparent, such as thin Celluloid mentioned, duplications of the recorded material may be obtained by ordinary photographic printing processes. Metal tape may be useful in connection with reproduction by other well known methods.

This tape 1, as illustrated in Fig. 2, may be fed from a supply roll 2 past the recorder station 3 onto a driving roll 4, and finally to a take up roll 5. The recorder 3 in Fig. 2 is illustrated as being

subjected to the impulses from a source of signals 6, through an amplifier 7. The recording of these impulses is accomplished by the printing process now to be described.

In Fig. 1 the impression or printing member 8 is shown generally as arranged transverse to the surface of the tape 1 and as having a narrow recording edge 9. This edge is transverse to the direction of the travel of the tape 1, although not necessarily at right angles thereto. By urging the impression member 8 transversely against the surface of the record blank 1, an impression or printing effect may be obtained. As the tape 1 is moved, the impression member 8 may be actuated toward the record blank with a pressure corresponding to the impulses to be recorded and to print a succession of lines or striations. One such line is illustrated at 10. The actual printing or marking may be accomplished by the aid of carbon paper, or printing ink in a manner to be described hereinafter. By appropriate choice of speed of the tape 1 past the impression member 8, satisfactory recording over a rather wide range of audio frequencies is attained.

In the diagram of Fig. 1, the broad idea of providing a printing effect by causing a printing pressure to be applied between the record blank 1 and the printing member 8 is illustrated.

In Fig. 3, the motion of the impression member 16 is in a direction illustrated by arrow 17, corresponding to a direction having a component that is normal to the surface of the tape 18. In this instance, the record 19 is formed of a substantially continuous series of closely spaced marks providing a variable density record. This is accomplished in view of the fact that the greater the printing impression produced by the impulses, the denser the individual marks are.

In Fig. 4, the record 21 on the moving tape or blank 26 is a combination of the variable area type and the variable density type. In this case the individual marks, comprising the series of marks in the record, have a variable length as well as variable density. This is accomplished by providing the impression member 22 with a narrow arcuate printing face 23, the curve of the face lying in a plane which is transverse to the surface of record 20 and transverse to the direction in which record 20 moves. As in the preceding form, impression member 22 moves in a direction having a component normal to the surface of the record 20. By appropriately supporting the moving tape 20 on a resiliently deformable platen, the resultant record produced by varying the pressure between member 22 and the tape 20 takes the form as illustrated by the record 21.

With light pressure between the printing member 23 and the platen a relatively narrow contact is had between the arcuate face of the printing member and the blank, and with heavy pressure the platen yields and affords wide contact between them. After the heavy pressure is removed the resilient platen returns to its original form and the narrow printing contact is restored. Thus the variable width feature of the record 21 is obtained.

The resiliently yielding platen is useful also in connection with the variable density feature of the record 21, or with the purely variable density record 19 in Fig. 3, inasmuch as it permits greater amplitudes of motion between the printing member and the record blank. If a hard, unyielding platen is used a series of sine wave impulses is distorted and recorded as a square topped wave

form, that is maximum printing effect is too quickly built up in the positive direction, and in the negative direction the pressure is totally released and the printing member jumps clear of the record blank. Only at very low amplitudes is faithful recording of impulses possible with a hard, unyielding platen, the volume range in recording is seriously restricted, and irregularities in the surface or thickness of the record blank have extreme deleterious effects. Some compensation is afforded by the yield under pressure of the record blank itself, but even so a hard platen is not very practical in recording by this method. By utilizing a resiliently yielding platen, faithful recording of impulse wave forms becomes possible, a range of volume levels may be recorded, and the effects of irregularities in surface or thickness of the record blank are minimized.

In Fig. 5 the platen 24 is shown as accommodated within a channel formed in a stationary support 25. Disposed and movable over the platen 24 is the record blank or paper strip 26. The printing or pressure member 27, shown in this case as provided with the narrow arcuate recording edge 28, is intended to contact the reverse side of a strip of carbon paper 29. This carbon paper 29 is interposed between the tape 26 and the recording edge 28, and is preferably fed slowly as its marking pigment is used up. The recording member 27 is indicated as guided in this instance for movement substantially normal to the surface of the tape 26, as in the stationary guides 30. This motion, as indicated by arrow 31, is produced in response to electrical impulses, as for example by the aid of a voice coil 32 mounted on a support 33 attached to the bottom of the impression member 27. The voice coil 32 is shown as disposed within the narrow air gap formed by the magnetic pole pieces 34 of a dynamic speaker unit. If desirable, a compression spring 35 may be utilized, providing normal pressure upon the member 27, even when no impulses are being received. However, such initial pressure may be provided in other well known ways, as for example by the aid of a direct current passing through the voice coil 32, supplementing the current impulses to be recorded. If a spring is used, its stiffness should be related to the compliance of the yielding platen, the mass of the moving parts, and the frictional resistances, so that the resultant record shall have the desired frequency response characteristics. Part of the control of frequency response can be obtained by suitable electrical design of the amplifier 1, and part by suitable mechanical design of the recorder itself.

In this form just illustrated, the carbon paper 29 interposed between the record blank 26 and the impression member 27 serves as a medium for providing the marking of the record, such as illustrated in Figs. 3 and 4. The resilient platen 24 insures that as the pressure upon the impression member 27 varies in accordance with the impulses to be recorded, the length of the transverse marks is varied, as well as their density.

In the form of the invention illustrated in Fig. 6, the member 36 operated by the dynamic coil arrangement 37, is shown as carrying the resilient platen 38 adapted to support the record blank or tape 39. This blank 39 is shown as urged against a printing wheel 40 supported on a stationary axis. The inking roller 41 is intended to apply an appropriate type of ink to

the narrow printing edge of the printing wheel 40. The carbon paper, of course, is omitted. Here the platen 38 and the tape 39 are preferably moved by the member 36, in order that the relatively massive impression wheel 40 and its inking roll 41 may be maintained on stationary axes. The periphery of the printing wheel 40 is provided with a series of very fine serrations 44, which serve to carry ink evenly across the area of contact with the tape. A smooth edged disc has a tendency to wipe off most of the ink at the approach side, resulting in a sound track that is very heavily inked on one side and lightly inked on the other. The serrations are fine so that a number are in contact with the tape at the same time, and they do not affect the recording. This form of the invention produces a record somewhat resembling that produced by the form illustrated in Fig. 5, but more nearly a purely variable area record. The ink here utilized is preferably somewhat thinner than the usual printer's ink, in order to render it more freely flowing.

In place of a thin disc impression roller, another type of printing wheel, such as illustrated in Figs. 7 and 8, may be utilized. The discs 42 and 43 forming the printing wheel proper, are spaced slightly apart to form a capillary passage 45 between them. This capillary passage is intended to be fed with appropriate inking fluid through an axial aperture 46. This roller structure may be driven, as by aid of a grooved pulley 47 joined in any appropriate manner to the hub 48 of the disc 43. The outer disc 42 is shown as threaded over the threaded extension 49 of the hub 48, and a check nut 50 serves to hold this disc in place with the proper narrow spacing between discs.

While this device may be used without rotation, it tends to gather dust and dirt from the moving tape and to become partially clogged. Rotation serves to wipe away the dirt and to continually present a fresh surface to the tape. In addition, centrifugal force helps gravity or other pressure to overcome capillary attraction and resistance to the flow of ink through the narrow passage between the discs, so that an extremely narrow intaglio inking surface is presented to the tape by the periphery of the wheel.

In all the forms illustrated the record is obtained immediately and can be played back without delay, by appropriate photoelectric means. In some instances the pressure effects produced by the printing member, such as the members 8, 16, 22, etc., may be used even without ink, to affect a sensitive photographic film. It has been found that variations in pressure, such as produced by the impression members, have generally the same effect as light. The tape carrying the sensitive film may then be developed in the usual manner to fix the record thereon.

What is claimed is:

1. In apparatus for recording impulses on the surface of a moving record blank, a serrated printing wheel adapted to print on said blank, the edge of the wheel being transverse to the travel of the blank, a platen for supporting the blank and capable of sustaining a printing pressure and means for pressing the blank and the edge toward each other in accordance with the impulses.

2. In apparatus for recording impulses by impression upon a flexible moving record blank, a platen having a resiliently yielding surface upon which said blank may be disposed, a rigid print-

ing member having a thin edge, adapted to make an impression upon the blank and against the resilience of the platen, and means creating the printing pressure in accordance with the impulses to be recorded.

3. In apparatus for recording impulses by impression upon a flexible moving record blank, a platen having a resiliently yielding surface upon which said blank may be disposed, a rigid printing member having a thin edge, adapted to make an impression upon the blank and against the resilience of the platen, said edge being so arched as to produce a combination variable area and variable density record, and means creating the printing pressure in accordance with the impulses to be recorded.

4. In apparatus for recording impulses by impression upon a flexible moving record blank, a

resiliently yielding platen upon which said blank may be disposed, a printing wheel formed of a pair of spaced wheel sections, and adapted to make an impression upon the blank and against the resilience of the platen, and means creating the printing pressure in accordance with the impulses to be recorded.

5. In apparatus of the character described, a moving record blank, a means forming resilient backing for the blank, a rigid printing member, having a thin printing edge disposed transversely to the direction of movement of the blank, and means to move said printing member in a direction having a component normal to the surface of the blank to make an impression thereon against the resilience of the support and in accordance with the impulses to be recorded.

LIVINGSTON MIDDLEDITCH.
